UNITED STATES PATENT OFFICE.

THOMAS S. HOMANS, OF HEMPSTEAD, NEW YORK, ASSIGNOR TO INTERNATIONAL TYPESETTING MACHINE COMPANY, OF NEW YORK, N. Y., A CORPORATION OF NEW YORK.

VICE FOR MACHINES OF THE LINOTYPE CLASS.

1,108,758.

Specification of Letters Patent.

Patented Aug. 25, 1914.

Application filed January 6, 1913. Serial No. 740,486.

To all whom it may concern:

Be it known that I, THOMAS S. HOMANS, a citizen of the United States, residing at Hempstead, in the county of Nassau and State of New York, have invented new and useful Improvements in Vises for Machines of the Linotype Class, of which the following is a specification.

This invention relates to improvements in line casting machines and more especially to those of the well known linotype class, and the primary object of the invention is to provide an improved vise for clamping the line of matrices endwise before the mold.

Machines of the linotype class employ a vise for such purpose and one of the vise jaws is normally in a fixed position, being movable only for special purposes, while the other vise jaw is movable automatically to clamp and release the line of matrices at appropriate intervals and is also capable of being moved to different set positions for the purpose of varying the space between the jaws and thereby accommodate lines of various lengths as may be required.

The improved device, according to the present invention, embodies means for quickly setting the movable vise jaw and for holding it accurately and securely in the different set positions, providing also for the automatic movements of the jaw as required.

In the accompanying drawings: Figure 1 is a plan view of a vise embodying the present invention, the vise being shown attached to the usual vise frame; Fig. 2 is a perspective view of the operating and setting mechanism for the movable jaw, these parts being detached from the framework; Fig. 3 is a detail perspective view of the adjusting rod guide; Fig. 4 is an end view, partly in section, showing the device on a reduced scale.

Similar parts are designated by the same reference characters in the several views.

In machines of the linotype class as at present used, the matrices are composed into a line by manipulation of the keyboard, and the line is then transferred to a position between two vise jaws preparatory to presentation of the line to the mold for the casting of a line of type. The vise jaws serve to confine the line of matrices in an endwise direction, the line of matrices being justified by expansion of the wedges of the spac-

ers, thereby causing the line of matrices to fill the space between the jaws which latter determine the length of the line. In the present instance, the normally fixed jaw which is movable only for special purposes is designated 1 and the movable jaw is designated 2, the jaw 1 being fixed to the vise frame 3 while the movable jaw is slideable on the vise frame in a direction toward and from the jaw 1 to vary the size of the opening between the jaws, according to the length of the line to be cast. An abutment 4, preferably in the form of a block, is also mounted to slide on the vise frame 3 and occupies a position behind the movable vise jaw 2, the latter being adapted to abut against the same. An adjusting rod 5 is attached to the abutment 4 and is arranged in parallelism with the line of movement of the movable vise jaw and its abutment. This adjusting rod is provided with a guide 6 which has a cylindrical exterior form and is slotted to receive the adjusting rod, the guide being contained in the cylindrical bore of a sleeve 7. This sleeve is provided at one side with a crank 8 which is operatively connected to the machine and is actuated automatically at appropriate intervals to shift the movable vise jaw toward and from the normally fixed jaw to clamp and release a line of matrices. In the present instance, a link 9 is pivotally connected to the crank 8, the link being connected to an operating lever 10, a coiled tension spring 11 serving to move the crank 8 in one direction while the lever 10 moves this crank in a reverse direction, this operating mechanism for the crank 8 being similar to that customarily used in machines of the linotype class. A nut 12 is threaded on one end of the sleeve 7, this nut being fitted in a bore formed in a bracket 13, the latter being fixed to the vise frame. The nut 12 has a flange 14 at one end which abuts against the adjacent portion of the bracket 13 whereby the latter may sustain the thrust exerted upon the nut 12 by the sleeve 7. The adjusting rod 5 is provided at its under side with a toothed rack 15, and a pinion 16 is provided to coöperate with the rack 15, rotation of the pinion serving to adjust the rod 5 longitudinally. This pinion 16 is fixed to a shaft 17, the latter being journaled in the bracket 13 and is capable of axial movement therein, a spring 18 interposed between the

pinion 16 and the bracket 13 serving to hold the shaft 17 in a predetermined position.

An adjusting knob having a dial 19 formed as a part thereof is fixed to the shaft 17 and is arranged at the front of the machine where it can be reached and manipulated easily by the operator. The dial is formed with a peripheral groove 20 to cooperate with the projection 21 on a slide 22. This slide has a portion which is provided with an aperture 23 through which the rod 5 passes, and one wall of this aperture is formed with teeth 24 to cooperate with the teeth of a rack 25, the latter being formed on one side of the adjusting rod 5. The slide 22 is capable of movement relatively to the bracket 13 and in unison with the axial shifting movements of the pinion shaft 17, movement of the pinion shaft 17 against the action of the spring 18 causing the slide 22 to shift forwardly and thereby disengage the teeth 24 thereon from the rack 25 on the adjusting rod, while a reverse axial movement of the pinion shaft under the influence of the spring 18 will cause reengagement of the teeth 24 of the slide with the rack 25 on the adjusting rod. While the slide 22 is disengaged from the rack on the adjusting rod, the latter is unlocked and may be shifted longitudinally to set the movable vise jaw in different positions by rotation of the pinion shaft 17, and when the desired setting has been made, a release of the operating knob will permit the spring 18 to return the pinion shaft and the slide 22 to locked position, thereby holding the jaw-operating mechanism at the desired adjustment. The dial 19 is preferably provided with graduations corresponding to the different settings for the vise, and the projection 21 of the slide 22 may be provided with an index mark 26 to cooperate with the graduations on the dial. The nut 12 is capable of rotation in its bearings in the bracket 13 in order to adjust the movable vise jaw in the event that the settings thereof should not correspond with those indicated by the graduations on the dial. This nut is locked when properly set by a set-screw 27. It is desirable occasionally to move the vise jaw 2 up against the jaw 1, this being done, for example, for the casting of blank lines. By forming the movable vise jaw 2 separately from the abutment 4, such an adjustment of the jaw 2 may be made without disturbing the setting of the abutment 4. It will be understood that the movable vise jaw 2 is moved back against the abutment 4 at each operation of the mechanism which conveys the line of matrices to the vise.

In order to change the position of the movable vise jaw from one setting to another, it is only necessary for the operator to pull the knob and dial forward and to turn the dial until the graduation corre-

sponding to the desired setting registers with the index mark 26, and when the operator releases his grip on the knob, the spring returns the parts automatically to a position where the slide 22 will lock the adjusting rod. The parts are so proportioned that the position of the movable vise jaw when resting against the abutment will correspond to the different settings represented by the graduations on the dial. The pressure incident to justification of the line of matrices by the expansion of the wedges of the spacers tends to spread apart the vise jaws, the pressure on the movable jaw producing a thrust on the adjusting rod 5 in a direction toward the left in Fig. 1. This thrust is transmitted by the adjusting rod to the slide 22, and this slide bears against the right hand end of the sleeve 7, the sleeve 7 transmitting the thrust to the nut 12 and the nut transmitting the thrust to the relatively fixed bracket 13 through the medium of the flange 14 on the nut. As this bracket 13 is securely fastened to the vise frame, it effectively resists the thrust. The operations of the movable vise jaw to clamp and release the line of matrices at appropriate intervals are effected by the lever 10 which may be of the form usually employed in machines of the linotype class. The spring 11 is fastened at its upper end to the relatively fixed bracket 13 and its lower end is hooked on the link 9, the spring constantly exerting an upward pull, tending to raise the link. When the lever 10 rises, it permits the spring 11 to raise the link 9 and thereby turn the crank 8 upwardly, and the thread engagement between the sleeve 7 to which the crank 8 is attached and the nut 12 which is fixed to the bracket 13 then causes the movable vise jaw 2 to move toward the fixed jaw and thereby clamp the line of matrices. A reverse motion of the lever 10 causes the crank 8 to be rocked downwardly against the action of the spring 11, the thread connection between the sleeve 7 and the nut 12 then moving the rod 5 in a reverse direction and permitting the abutment 4 and vise jaw 2 to recede and thereby release the line of matrices. There is sufficient side play between the slide 22 and the relatively fixed bracket 13 to permit the adjusting rod 5 and the slide 22 to move to and fro in this manner without disturbing the bearing of the slide 22 against the crank 8.

I claim as my invention:

1. In a machine of the linotype class, in combination, a movable vise jaw, an adjusting rod for setting said jaw, a pinion meshed with said rod for setting said jaw in different positions, said pinion having a dial rotatable therewith for indicating the different set positions of said vise jaw, and means for holding the vise jaw in position when set.

2. In a machine of the linotype class, in combination, a movable vise jaw, a toothed adjusting rod for setting said jaw and independent thereof, a pinion meshed with said rod comprising a handle for rotating the same supplied with means for indicating the position of the adjusting rod, and means for locking the adjusting rod in any desired and indicated position. 40
- 5 3. In a machine of the linotype class, the combination with a normally fixed matrix vise jaw and a relatively movable vise jaw, of means for adjusting said movable jaw embodying a knob or handle capable of rotary and axial movement, means operative by the rotative movement thereof for moving said movable jaw, and means operative by the axial movement of the knob or handle for locking or unlocking the movable jaw. 50
- 10 4. In a machine of the linotype class, in combination, a movable vise jaw, a threaded member provided with means for turning it automatically to close and open the jaw, a toothed adjusting rod passing through said threaded member, and a detent or lock adapted to engage said toothed rod and to bear against the end of said threaded member. 60
- 15 5. A vise for machines of the linotype class embodying a movable jaw, an adjusting member therefor, means for reciprocating said member to cause the jaw to clamp and release a line embodying a rotatable sleeve through which said member extends, a device for setting said member in different positions relatively to said sleeve, and means 65
- 20 for locking said member in different set positions. 70
- 25 6. A vise for machines of the linotype class embodying a movable jaw, an adjusting member therefor, means for reciprocating said member to cause the jaw to clamp and release a line embodying a rotatable sleeve through which said member extends, a device for setting said member in different positions relatively to said means, and means controlled by said setting device for locking said member in different set positions. 75
- 30 7. A vise for machines of the linotype class embodying a movable jaw, an adjusting member therefor, means for reciprocating said member, a pinion rotatable to set said member in different positions relatively to said means, the pinion being capable of axial movement, and a device controlled by the axial movement of the pinion for locking said member in different set positions. 80
- 35 8. A vise for machines of the linotype class embodying a movable jaw, an adjusting member therefor, means for reciprocating said member, a pinion rotatable to set said member in different positions relatively to said means, the pinion being capable of axial movement, and a slide movable axially with the pinion to thereby lock and unlock said member. 85

In testimony whereof I have hereunto set my hand in presence of two subscribing witnesses.
